UNITED STATES PATENT OFFICE.

ISRAEL BERMAN, OF NEW YORK, N. Y., ASSIGNOR TO MELROSE SLIPPER CO. INC., OF NEW YORK, N. Y., A CORPORATION OF NEW YORK.

DESIGN FOR A SLIPPER OR ANALOGOUS ARTICLE.

Application filed February 12, 1929. Serial No. 30,034. Term of patent 3½ years.

To all whom it may concern:

Be it known that I, ISRAEL BERMAN, a citizen of the United States, and a resident of New York, in the county of New York and State of New York, have invented a new, original, and ornamental Design for a Slipper or Analogous Article, of which the following is a specification, reference being had to the accompanying drawing, forming a part thereof.

Fig. 1 is a front perspective view of a slipper or analogous article, showing my new design, the dominant feature of which is the surface ornamentation on the vamp; and Fig. 2 shows the surface ornamentation on an enlarged scale on half of the vamp, it being understood that the other half is similarly ornamented as the half shown:

I claim:

The ornamental design for a slipper or analogous article, substantially as shown and described.
